(57) **CLAIM**

The ornamental design for a covered mixing valve as shown and described.

DESCRIPTION

FIG. 1 is a front perspective view of a covered mixing valve. FIG. 2 is a back perspective view of the covered mixing valve.

FIG. 3 is a front view of the covered mixing valve.

FIG. 4 is a back view of the covered mixing valve.

FIG. 5 is a right side view of the covered mixing valve.

FIG. 6 is a left side view of the covered mixing valve.

FIG. 7 is a top view of the covered mixing valve; and,

FIG. 8 is a bottom view of the covered mixing valve. The broken lines in the figures show features of the covered mixing valve that form no part of the claimed design.
